UNITED STATES PATENT OFFICE.

HENRY L. KOEHLER, OF LOUISVILLE, KENTUCKY.

BURNING-PRESS.

1,092,776.

Specification of Letters Patent.

Patented Apr. 7, 1914.

Application filed July 22, 1913. Serial No. 780,521.

To all whom it may concern:

Be it known that I, HENRY L. KOEHLER, a citizen of the United States, residing at Louisville, in the county of Jefferson and 5 State of Kentucky, have invented new and useful Improvements in Burning-Presses, of which the following is a specification.

This invention relates to burning presses, the object in view being to provide a rotary 10 press which will quickly and effectively burn letters, monograms, designs, and printed matter of all descriptions on any kind of wood, fiber, card-board, or various kinds of material of any thickness, the machine embodying means for keeping in a properly 15 heated condition a cylindrical or segmental form bearing the type, letters, designs, monograms, etc., to be burned into the material referred to.

20 A further object is to provide means for regulating the area of the flame used for heating the type form; also means for gag- 25 ing the position of the work and the delivery of the same to the burning cylinder.

25 A further object of the invention is to pro- 30 vide novel and effective means for intermittently feeding the boards or other form of work to the burning cylinder at the proper period of time, to cause the impression to be made on the board in proper relation to the margins thereof.

With the above and other objects in view, the invention consists in the construction, 35 combination and arrangement of parts, as will be hereinafter more fully described, illustrated in the accompanying drawings, and pointed out in the claims hereunto appended.

40 In the drawings: Figure 1 is a side elevation of a rotary burning machine, embodying the present invention, the same being partly broken away in section to better illustrate some of the details. Fig. 2 is a plan view of the same. Fig. 3 is a vertical section 45 taken in line with the main burning cylinder shaft. Fig. 4 is a detail side elevation showing the work supporting table and one of the lateral gages. Fig. 5 is a vertical section through the table taken at right angles to 50 Fig. 4. Fig. 6 is a face view of the front gage plate or cut off. Fig. 7 is a front edge view of the table. Fig. 8 is a side view of one of the end supports or heads of the

burning cylinder. Fig. 9 is a side elevation of one of the central disks or supports 55 for the tubular burners. Fig. 10 is a side elevation of the gas manifolds of the burning cylinder, showing the arrangement of stop cocks therefor. Fig. 11 is a detail section through one-half of the same, showing 60 one of the manifolds and the parts connected therewith. Fig. 12 is a detail section showing the driving mechanism for the im- 65 pression roller. Fig. 13 is a vertical fore and aft section showing the manner in which the work table is supported.

The rotary burning machine contemplated in this invention embodies a suitable frame for supporting the operative elements of the machine, and in the preferred embodiment thereof, this frame consists of the two side members 1 and 2 which are pro- 70 vided with suitable flanges 3 adapted to receive lag screws for bolting the machine frame as a whole to the floor. The side 75 frame pieces 1 and 2 are also connected by cross tie bolts 4, any number of which may be employed. Mounted in bearings 5 in the upper portion of the frame pieces 1 and 2 is the main burning cylinder shaft 6, 80 the same being held in place by cap pieces 7 secured by bolts 8.

The burning cylinder comprises two op- 85 positely arranged heads or disk-shaped sup- ports 9, the hubs 10 of which are fast on the shaft, and in addition thereto several intermediate or central disk-shaped sup- 90 ports 11. Each of these supporting mem- bers 9 and 11, all of which are fast on the shaft 6, is provided with an annular series of holes 12, which receive a corresponding 95 number of tubular burners 13. Each of said burners consists of a tubing of suitable length, provided throughout the length thereof with any desired number of perfor- 100 tions of suitable size, through which the vapor escapes, and is ignited so as to form a practically continuous flame which operates against the inner surface of the type form, hereinafter referred to. The mem- bers 11 are also perforated at 13' to allow the heat to pass through them. Each of said tubular burners is closed at one end, as shown at 14, and provided at such end with means for turning the same on its 105 longitudinal axis, the means shown consist-

ing of a screw driver notch 15. At its opposite end, each tubular burner 2 is threaded as shown at 16, and screwed into an internally threaded opening in a manifold 17.

5 By now referring to Fig. 10, it will be seen that I employ a circular series of manifolds 17, to each of which a certain number of tubular burners 13 is connected. Each manifold 17 is provided with an inwardly 10 extending radial feed pipe 18 which communicates with a central longitudinal bore 19 in the shaft 6, as shown in Fig. 3. Each feed pipe 18 is also provided with an individual stop cock 20, so that the supply of 15 gas may be cut off therefrom, when a form less than a complete cylinder is employed.

The type form shown at 21 is in the form 20 of a hollow cylinder or segment of a cylinder, and the opposite edges thereof are chamfered, as shown at 22, so as to be engaged by oppositely arranged sets of clamps 23, each provided with a V-shaped notch 24 to engage one end of the type form. Each 25 of the clamps 23 is also provided with an internally threaded opening 25 to receive a threaded adjusting or clamping screw 26, one end of which is squared, as shown at 27, to enable the same to be turned with the aid of a suitable wrench. Each screw 26 is provided 30 at its opposite ends with reduced journal portions 28 which are received in holes 29 and 30 in the intermediate and end supports 11 and 9 of the burning cylinder, as indicated in Fig. 3. Screws 30' are also inserted 35 through the form 21 into the supports 11 as shown in Fig. 3.

From the foregoing description, it will be 40 seen that the burning cylinder is made up of a circular series of tubular burners, and that the type form is in the form of a hollow 45 cylindrical sheet which extends around and is supported outside of said tubular burners, and is held in place by screws and oppositely arranged sets of sliding clamps which are moved toward and away from the 50 chamfered edges of the form by means of adjusting or clamping screws.

The radial feed pipes 18 of the manifolds 55 17 all enter a common box or hollow distributing collar 31, at opposite sides of which are arranged stuffing boxes 32 and 33 to provide a gas-tight joint between said pipes 18 and the shaft 6. Gas, gasolene, or other vapor or oil may be fed through the hollow bore of the shaft 6 from any source of supply, and by means of any suitable connection, the gas passing through holes 33' in the shaft 6 into the distributing collar 31, and thence through the pipes 18 to the manifolds 60 17 and burners 13.

Arranged directly beneath the burning cylinder is an impression roller 34 mounted loose on the shaft 35 supported in bearing boxes 36, which are slidable up and down in guide ways 37 between parallel guide ribs

37' on the frame pieces 1 and 2, above described. The boxes 36 rest upon yielding supports or cushions 38, consisting of blocks of rubber supported by saddles 39 adjustable up and down by means of screws 40 passing through internally threaded portions 41 of the side members of the machine frame, as shown in Fig. 1. Collars 42 held by set screws on the shaft 35 prevent end movement of the roller 34.

43 designates the work supporting table which is provided with parallel grooves 44, in the upper face thereof, adapted to guide a pair of parallel feed chains 45 provided with oppositely arranged sets of detachable and adjustable teeth 46 forming projecting shoulders adapted to engage the rear edge of a board or piece of work, so as to advance the work to the burning cylinder. These chains 45 pass around wheels 46 set into the impression roller 34, as shown in Fig. 3, and at their opposite ends are passed around wheels 47 on a shaft 48 journaled in bracket arms 49 which are adjustable in and out relatively to the frame of the machine, as shown in Fig. 1, each of said bracket arms being provided with a laterally extending lug 50 which receives an adjusting screw 51 impinging at its inner end against the frame. This enables the chains to be tightened, so that they will accurately feed the work inward to the burning cylinder. Each bracket arm 49 is held fast by a binding screw or bolt 52 passing through a horizontal slot 53 in the machine frame, thereby enabling the operator to fix the adjustment of the bracket arms. The table 43 is also provided with the laterally extending slots 54 adapted to receive flanges 55 on the bottoms of a pair of sliding brackets or arms 56, each of which is provided with a broad base 57 which rests on and slides in contact with the upper surface of the table. Secured to each pair of bracket arms 56 is a face plate 58 which forms one of the side gages, between which the sheets or boards are placed, preparatory to their being fed inwardly one at a time and submitted to the action of the burning cylinders. The arms or brackets 56 are further provided with holes to receive clamping screws 59 which pass through the slots 54 in the table, and are tightened by means of thumb nuts 60 for fixing the adjustment of the lateral gages. The arms or brackets 56 are further provided with holes 61 adapted to receive bolts 62 which pass through slots 63 in a front face plate or gage or cut-off 64. This cut-off is in the form of a plate which is connected to the lateral gages in the manner just hereinabove described, and which is adjustable to a slight extent in a vertical direction, so that the bottom edge thereof may be raised to any necessary elevation above the top surface of the table in accordance with the thickness of the board or other

sheet of material being operated upon, the idea being that when the bottom board or sheet of the pile is allowed to pass under the gage plate 64, the remainder of the pile or 5 stack being restrained and held back by said plate, which thus acts as a cut-off.

Near its front edge, the table 43 is provided on its under side with knuckles 65, through which passes one of the tie bolts or 10 rods 4 forming a pivotal support for that edge of the table. At its inner edge, the table is provided with forks 66 which embrace the shaft 35 of the impression roller and support such edge of the table thereon, 15 so that it rises and falls with the impression roller, in accordance with the thickness of the work being fed to the burning cylinder.

The driving shaft 67 is journaled at one end in the machine frame, and at its other 20 end in a bracket 68 projecting from the frame, and is shown equipped with a cone pulley 69 to provide for variable speed. A spur pinion 70 fast on the shaft 67 drives a large gear wheel 71 on the shaft 6 of the 25 burning cylinder, and also drives a pinion 72 on a short hollow shaft or sleeve 73 supported by a stud shaft 74 projecting outwardly from the machine frame, as in Fig. 3. Fast on the same sleeve or shaft 73 is a sprocket 30 wheel 75, from which a chain 76 extends around another sprocket wheel 77 fast on the end of the shaft 48 which drives the feed chains 45. By the mechanism just described, motion is imparted to the burning 35 cylinder and feed chains, and the impression roller is permitted to move toward and away from the burning cylinder.

Where the type form is less than an entire hollow cylinder, it will be apparent that 40 by means of the stop cocks 20, one or more of the manifolds 17 may be cut out and consequently the tubular burners 13 which are supplied by said manifolds. The burning cylinder is therefore adaptable to forms of 45 widely varying sizes.

What is claimed is:

1. A burning press, comprising a machine frame, a work supporting table, a rotary type carrying and heating cylinder operating above the plane of the table, and a self-adjusting impression roller, said cylinder embodying a shaft, a circular series of tubular burners, and a manifold to which said burners are connected.

55 2. A burning press, comprising a machine frame, a work supporting table, a rotary type carrying and heating cylinder operating above the plane of the table, and means for regulating the impression of said cylinder, said cylinder embodying a shaft, a circular series of tubular burners, type form supports, and a manifold to which said burners are connected.

60 3. A burning press, comprising a machine frame, a work supporting table, a rotary

type carrying and heating cylinder operating above the plane of the table, means for regulating the impression of said cylinder, said cylinder embodying a shaft, a circular series of tubular burners, type form supports, and a manifold to which said burners are connected, and means for clamping a type form on said cylinder. 70

4. A burning press, comprising a machine frame, a work supporting table, a rotary type carrying and heating cylinder operating above the plane of the table, means for regulating the impression of said cylinder, said cylinder embodying a shaft, a circular series of tubular burners, type form supports, a manifold to which said burners are connected, and screw operated clamps working between the burners for holding a type form on the cylinder. 75

5. A burning press, comprising a machine frame, a work supporting table, a rotary type carrying and heating cylinder operating above the plane of the table, means for regulating the impression of said cylinder, said cylinder embodying a shaft, a circular series of tubular burners, type form supports through which the burners pass, and a manifold to which said burners are connected. 80

6. A burning press, comprising a machine frame, a work supporting table, a rotary type carrying and heating cylinder operating above the plane of the table, and means for regulating the impression of said cylinder, said cylinder embodying a circular series of parallel tubular burners, and an annular series of manifolds each having its proportion of burners communicating therewith. 95

7. A burning press, comprising a machine frame, a work supporting table, a rotary type carrying and heating cylinder operating above the plane of the table, means for regulating the impression of said cylinder, said cylinder embodying a circular series of parallel tubular burners, an annular series of manifolds each having its proportion of burners communicating therewith, and a stop cock for each manifold. 105

8. A burning press, comprising a machine frame, a work supporting table, a rotary type carrying and heating cylinder operating above the plane of the table, and means for regulating the impression of said cylinder, said cylinder embodying a shaft having a gas inlet passage therein, a circular series of parallel tubular burners, an annular series of manifolds to which the burners are connected, and pipes leading from each manifold to said inlet passage. 115

9. A burning press, comprising a machine frame, a work supporting table, a rotary type carrying and heating cylinder operating above the plane of the table, means for regulating the impression of said cylinder, 130

said cylinder embodying a shaft having a gas inlet passage therein, a circular series of parallel tubular burners, an annular series of manifolds to which the burners are connected, pipes leading from each manifold to said inlet passage, and a stop cock connected with each of said pipes.

In testimony whereof I affix my signature in presence of two witnesses.

HENRY L. KOEHLER.
